UNITED STATES PATENT OFFICE.

JOSEPH LEE ROUSSEAU, OF BROOKLYN, NEW YORK, ASSIGNOR TO MERGENTHALER LINOTYPE COMPANY, A CORPORATION OF NEW YORK.

TYPE OR MATRIX.

1,214,373.

Specification of Letters Patent. Patented Jan. 30, 1917.

Application filed April 6, 1915. Serial No. 19,430.

To all whom it may concern:

Be it known that I, JOSEPH LEE ROUSSEAU, a citizen of the United States, residing at Brooklyn, in the county of Kings and State 5 of New York, have invented certain new and useful Improvements in Type or Matrices, of which the following is a specification, reference being had therein to the accompanying drawing.

10 My invention relates to matrices, such as are employed in linotype machines of the general organization represented in Letters Patent of the United States, No. 436,532, to O. Mergenthaler. In machines of this 15 class, the matrices are released from a magazine by the manipulation of a keyboard, assembled in line, and then presented to a mold, wherein the slug or linotype is cast, after which they are distributed and returned to the magazine from which they 20 started.

Under modern conditions, it is common to employ matrices of large size or of great thickness, such, for instance, as those formed 25 with "head letter" or "display" characters. In the use of such thick matrices, it is found that their great weight causes undue wear on their tooth combinations and on those on the distributor bar, as well as wear on 30 other parts of the machine due to their violent impact thereon. In order to relieve the parts of such excessive wear, the matrices heretofore have ordinarily been constructed in skeleton form, or more specifically, 35 longitudinal cuts or grooves have been made in their side faces to remove as much metal as possible. As a result, other difficulties arise, and particularly in that the necessary support is taken away from the 40 front edges of the matrices, wherein the formative characters are located, and further there is the liability that the walls may sink or fall inwardly, causing the matrices to lose their proper rectangular form, so 45 that they will fail to lock up properly in the assembled line or fit closely against the mold when presented thereto. Various other difficulties will be obvious to those skilled in the art.

50 It is the aim of my present invention to avoid the above objections or any liability thereto, and to this end I propose to cut or hollow out the main portion of the matrix lying between its side walls, so that in other 55 respects it will retain its ordinary form and

contour. In other words, I form the matrix with an interior channel or cavity which will lie between and be inclosed by its side walls, so that the latter may give firm support to the front edge of the matrix containing the formative cavity, and so that the general form and configuration of the matrix may be preserved. In short, this construction will not only permit a great reduction in the weight of the matrices but 60 at the same time will maintain their proper shape and size.

I have illustrated my invention as applied to a very large or thick matrix of the display variety, but obviously many changes 70 and variations may be made in the mode of application and also in its size and form, which will still be comprised within the spirit of my invention. Similarly, the invention may be adapted to type or dies as 75 well as matrices.

Generally speaking, I desire it to be understood that I do not limit myself to any specific form or embodiment, except in so far as such limitations are specified in the 80 claims.

Referring to the drawing: Figure 1 is a perspective view of the matrix constructed in accordance with my invention; Fig. 2 is a vertical section; Fig. 3 is a section on the 85 line 3—3 of Fig. 2; and Fig. 4 is a modification.

In the drawing, I have shown a matrix A of the general construction disclosed and described in Letters Patent No. 1,120,614 to 90 A. W. F. Guest, it being provided at its opposite edges with the two sets of guiding and supporting ears A¹ and A² respectively, and formed at its upper end with the tooth-combination A³. As usual, the matrix is 95 also provided in its front edge with the formative character A⁴.

Referring to Figs. 1, 2 and 3, it will be noted that the matrix A is bored or hollowed out both from its top and bottom edges to 100 produce ellipsoidal channels or cavities, B and B¹, extending longitudinally thereof and separated by an intermediate horizontal wall or partition B², located behind the formative character A⁴. As a result of this 105 construction, the side walls or faces of the matrix remain unimpaired, the above mentioned channels being located between and inclosed by them. Also, the weight of the matrix is greatly reduced, without taking 110

away the requisite support for its front edge which contains the formative character, it being noted that such support is furnished both by the side walls of the matrix and the intermediate partition B². The matrix shown in Fig. 4 is the same as that just described, except that it is provided with a single cavity or channel C which extends entirely throughout its length, opening both at its bottom and top.

The matrix in both forms may be provided in one of its side walls at the upper end with a longitudinal cut or notch A⁵, opening into the interior channels B or C, and designed to coöperate with the fixed stop in the distributor box as the matrix is lifted therefrom for delivery to the distributing mechanism, as well understood in the art.

It will be noted (see Fig. 3) that the interior channels are so formed and located so as to reduce the opposite side wall of the matrix at its upper end as at A⁷, to allow it, when lifted, to pass the fixed stop just referred to. The longitudinal notch and the interior channel of the matrix thus serve conjointly to make up the so-called separating notch which is present in the common form of matrices. Heretofore these separating notches have been formed by means of a rotary saw having a considerable radius, and have consequently acquired great extent in matrices of substantial thickness, extending practically throughout their length and resulting in an appreciable weakening. This weakening becomes quite serious in connection with the thicker matrices and principally those having head-letter or display characters, because the notches are not only necessarily of greater depth and length, but in addition such large matrices have commonly been formed with other longitudinal notches or grooves to remove as much metal as possible to lighten them. These objections are overcome in the present form of matrix, in that the longitudinal cuts or notches A⁵ are only of such extent as is necessary to allow the matrices to clear the overlying stop rail during their detachment from the line, the notches being of small and uniform extent throughout the set or font and thereby avoiding the weakening of the matrix bodies. In addition, the manufacture of the matrices is materially facilitated, the interior cavities B or C usually first being drilled therein from one end or the other, and the cut or notch A⁵ next cut through the side wall by means of a suitable tool such as a milling or planing tool or the like; and if desired, an air blast may be employed during the slotting process to blow off the chips, the interior cavities furnishing a good exit therefor and greatly facilitating the operation. The matrices may thus not only be formed with separating notches of the short

and uniform length described, but their manufacture may be materially simplified and the expense correspondingly reduced.

The matrix is also provided at its lower edge with a cut or notch A⁶ passing transversely through its side walls and designed to coöperate with a font selecting bridge, in the well known manner. It will be thus seen that the interior channel of the matrix in no way affects the use of the notch but rather serves conjointly with such notch to permit the proper coöperation of the matrix with the font selecting bridge.

As previously stated, I have shown my invention only in preferred form and by way of example, and as applied to a specific style of matrix. However, many modifications and alterations therein, and in its mode of application, will readily suggest themselves to those skilled in the art, without departure from its scope.

Having thus described my invention, its construction and mode of operation, what I claim and desire to secure by Letters Patent of the United States is, as follows:

1. A type or matrix of rectangular elongated form containing a formative character in one of its vertical edges and provided at its upper end with a distributing combination and on its opposite edges with projecting ears to adapt it for circulation in a typographical machine, the said type or matrix having solid or rigid side and edge walls and formed with a channel or cavity located between and inclosed by said walls; whereby the matrix is materially lightened without weakening it, without destroying its general form or contour, and without removing the support from its edge wall containing the formative character.

2. A type or matrix of rectangular elongated form containing a formative character in one of its vertical edges and provided at its upper end with a distributing combination and on its opposite edges with projecting ears to adapt it for circulation in a typographical machine, the said type or matrix having solid or rigid side and edge walls and formed with two longitudinal channels or cavities located between and inclosed by said walls and extending from its top and bottom, respectively, and separated by an intermediate partition which is located in the rear of the formative character; whereby the matrix is materially lightened without weakening it, without destroying its general form or contour, and without removing the support from its edge wall containing the formative character.

3. A type or matrix adapted for circulation in a typographical machine and formed at its upper end with a channel or cavity located between and inclosed by its side walls, one of said walls being reduced at its upper end by said channel, and the other formed

with a longitudinal cut or notch opening into the channel, the said cavity and notch thus serving conjointly to provide a separating notch adapted to coöperate with the stop rail of a distributer box used in said typographical machine, substantially as shown and described.

4. A type or matrix A adapted for circulation in a typographical machine and formed with a channel or cavity located between and inclosed by its side and edge walls and opening at its bottom, the said type or matrix being formed in its bottom with a cut

or notch extending transversely through said side walls, the said cavity and notch thus serving conjointly to provide a distributing notch adapted to coöperate with a font-selecting bridge used in said machine, substantially as shown and described.

In testimony whereof, I have affixed my signature in presence of two witnesses.

JOSEPH LEE ROUSSEAU.
